UNITED STATES PATENT OFFICE.

RICHARD SMITH, OF PHILADELPHIA, PENNSYLVANIA, ASSIGNOR TO
MACKELLAR, SMITHS & JORDAN, OF SAME PLACE.

DESIGN FOR PRINTING-TYPE.

Specification forming part of Design No. 7,348, dated March 31, 1874; application filed March 19, 1874.
[Term of Patent 7 years]

To all whom it may concern:

Be it known that I, RICHARD SMITH, (assignor to MACKELLAR, SMITHS & JORDAN,) of the city and county of Philadelphia, Pennsylvania, have invented and produced a new and original Design for Printing-Types, of which the following is a specification:

The nature of my design is fully shown in

the accompanying typographic impressions, to which reference is made.

What I claim as new is—

The design for printing-types, as shown.
RICHARD SMITH.

In presence of—

GEO. WM. WITHAM,
C. F. HUCH.
